UNITED STATES PATENT OFFICE.

AMBROSE GIRAUDAT, OF NEUVY, (NORWOOD P. O.,) NEW JERSEY.

IMPROVEMENT IN MACHINES FOR CUTTING STAMENS FOR ARTIFICIAL FLOWERS.

Specification forming part of Letters Patent No. 175,069, dated March 21, 1876; application filed January 7, 1876.

To all whom it may concern:

Be it known that I, AMBROSE GIRAUDAT, of Neuvy, (Norwood P. O.,) in the county of Bergen and State of New Jersey, have invented a new and useful Improvement in Thread-Cutting Machine for Making Stamens for Artificial Flowers, of which the following is a specification:

Figure 1 is a top view of my improved machine. Fig. 2 is a vertical cross-section of the same, taken through the line *x x*, Fig. 1. Fig. 3 is a vertical longitudinal section of the same, taken through the line *y y*, Fig. 1.

Similar letters of reference indicate corresponding parts.

The object of this invention is to furnish an improved machine for cutting threads into suitable lengths for the stamens of artificial flowers, which shall be so constructed as to cut the threads evenly and of uniform length, and which shall be simple in construction and convenient in use, doing its work rapidly and well.

The invention consists in the combination of the long straight knives and their holders, and the rollers, the brackets, and the springs, with the hinged beam and its frame or carriage, and the bed-plate of the machine, as herein-after fully described.

A is the frame of the machine, to the middle part of which is attached the bed-plate *B*, which is so made that its upper part may be free all around and of such a size as to fit into the frame that holds the threads. To the bed-plate *B* are attached pairs of bars *C*, the bars of each pair being at such a distance apart as to receive a knife or cutter, *D*, between them. The pairs of bars *C* are secured to the bed-plate *B* in such positions that the width of the spaces between the knives *D* may be equal to the required length of the threads. *E* is a bar extending across the machine, and which is hinged at its lower rear angle to a rod, *F*, attached at its center and ends to a bar, *G*, which is so bent that its end parts may be at right angles with the rod *F*. To the ends of the bar *G* are pivoted small wheels *H*, which roll along ways *N* attached to the upwardly-projecting parts of the ends

of the frame *A*. The rear parts of the bar *G* are kept from rising by guides *h'* attached to them at their angles, and which slide along the ways *N*. To the lower side of the bar *E* are loosely attached brackets *I*, which project in front of said bar and have small rollers *K* pivoted to them, the brackets *I* being in such positions that the rollers *K* may roll along the edges of the cutters *D* to cut off the threads. The rollers *K* are held down with sufficient force to cut the threads by springs *L* attached to the beam *E*, and which bear upon the upper side of the forward ends of the brackets *I*. The beam *E* and its attached rollers *K* are moved back and forth by a handle, *M*, attached to the said beam *E*. The threads are held between the cutters *D*, so that they will not get out of their proper relative positions, by sticks or clamps *P* placed between the knife-holders *C*. After the threads have been cut the sticks *P* are taken from the machine and the ends of the threads are dipped into paste to form anthers, seed-vessels, or fruit, as may be desired.

This construction allows the beam *E* and its attached brackets and rollers to be turned back out of the way for convenience in applying and removing the frame *Q* when desired. The forward movement of the beam *E* and its attachments is limited by stops *O* attached to the frame *A*. With this construction the threads are cut upon the long straight knives so that they will be cut evenly and of uniform length. This construction enables the knives *D* to be easily taken out and conveniently sharpened.

Having thus described my invention, I claim as new, and desire to secure by Letters Patent—

The combination of the long straight knives *D* and their holders *G* and the rollers *K*, the brackets *I*, and the springs *L* with the hinged beam *E* and its frame or carriage, and the bed-plate *B* of the machine, substantially as herein shown and described.

AMBROSE GIRAUDAT.
